UNITED STATES PATENT OFFICE.

GEORGE WILBUR SPENCER, OF ATLANTIC CITY, NEW JERSEY, ASSIGNOR OF ONE-HALF TO HARRY J. SHILL, JR., OF ATLANTIC CITY, NEW JERSEY.

BUSHING.

No. 889,055.

Specification of Letters Patent.

Patented May 26, 1908.

Application filed April 15, 1907. Serial No. 368,410.

To all whom it may concern:

Be it known that I, GEORGE WILBUR SPENCER, a citizen of the United States, and a resident of Atlantic City, in the county of 5 Atlantic and State of New Jersey, have invented a new and Improved Bushing, of which the following is a full, clear, and exact description.

The invention relates to bushings used in 10 connection with devices for tapping kegs, barrels and other receptacles containing sparkling liquids, and its object is to provide a new and improved bushing, arranged to form a very tight joint between the tapping 15 device and the wall of the bung hole, to prevent leakage.

The invention consists of novel features 20 and parts and combinations of the same, which will be more fully described herein- 25 after and then pointed out in the claims.

A practical embodiment of the invention is represented in the accompanying drawings forming a part of this specification, in which similar characters of reference indicate corresponding parts in all the views.

Figure 1 is a side elevation of the improvement in position on the driving device, and arranged over the head of the receptacle, the said head being shown in section; Fig. 2 is a 30 sectional side elevation of the same in position on the head of the receptacle; Fig. 3 is a perspective view of the bushing, and Fig. 4 is a sectional side elevation of the same.

The improved bushing consists of a shell 35 or a body A made of paper or other suitable compressible material, the shell being frusto-conical in form and its base end A' being open and its apex end A² being closed, the apex end A² extending inwardly, as plainly indicated in Fig. 4. The wall of the shell A, between the ends at approximately its longitudinal center, is provided with perforations A³, to permit the shell to separate when driven home, as hereinafter more fully 45 described. The shell A is adapted to fit onto the conical part B' of the usual driving device B employed for driving the bung or cork C inward in the head D of the keg, barrel or other receptacle to be tapped, it 50 being understood that when the driving de-

vice B with the shell A thereon is driven home, as illustrated in Fig. 2, then the shell A fits into the bung hole and the tapping can now be completed by forcing the usual tapping pipe E through the driving device 55 B and against the end A² so as to perforate the same and to pass into the contents of the receptacle. Now during the driving home of the driving device B, the shell A is strained to a considerable extent by the end 60 of the tapering portion B' abutting against the closed end A² of the shell A, and consequently the shell A is liable to be torn apart along the perforations A³, but at the same time the outer portion of the shell A is 65 driven tightly in contact with the wall of the bung hole, so as to form an exceedingly tight joint between the wall of the bung hole and the tapering portion B' of the driving device B. It is understood that when the inner 70 end portion of the shell A is strained and torn, the outer portion is not seriously affected to cause leakage, as is so frequently the case with bushings heretofore constructed.

It will be noticed that applicant's device is a frusto-conical shell having its larger end open to receive the driving device, and that the said shell is partially separated or provided with a weakened annular line at approximately 75 its longitudinal center to permit rupture of the shell on the line of this partial separation during the driving, in order to prevent longitudinal rupture of the upper part of the shell by the driving device.

Having thus described my invention, I claim as new and desire to secure by Letters Patent:

1. In a device for tapping barrels, a frusto-conical shell having its large end open to receive the driving device, said shell having an annular series of perforations at approximately its longitudinal center, to permit the rupture of the shell on the line of perforation during the driving to prevent longitudinal rupture of the upper part of the shell by the driving device.

2. In a device for tapping barrels, a frusto-conical shell having its large end open to receive the driving device, said shell being

provided with a weakened annular line at
approximately its center to permit the rup-
ture of the shell on the weakened line during
the driving to prevent longitudinal rupture
5 of the upper part of the shell by the driving
device.

In testimony whereof I have signed my

name to this specification in the presence of
two subscribing witnesses.

GEORGE WILBUR SPENCER.
